UNITED STATES PATENT OFFICE.

R. W. AND DANIEL DAVIS, OF YELLOW SPRINGS, OHIO.

MACHINE FOR PRINTING THE ADDRESS ON NEWSPAPERS, &c.

Specification of Letters Patent No. 25,319, dated September 6, 1859.

To all whom it may concern:

Be it known that we, R. W. DAVIS and DANIEL DAVIS, of Yellow Springs, in the county of Greene and State of Ohio, have 5 invented a new and useful Improvement in Machines for Printing the Address on Newspapers, &c.; and we do hereby declare that the following is a full and clear description thereof, reference being had to the accompanying drawings, and to the letters of reference marked thereon and made to form a part of this description.

Our invention relates, 1st, to the employment of wooden blocks, having indented letters, in their faces, for printing the address on newspapers; 2d, to the arrangement of said blocks upon a flexible belt or band; 3d, to a device for separating said blocks at the printing point in such manner 20 that each block may deliver its impression without interference from, or by other blocks; 4th, a device for properly adjusting the feed wheel with reference to the bed.

In reference to the accompanying drawings, Figure 1, is a perspective view, showing the printing machine arranged for use. Fig. 2, is a vertical sectional view, showing the manner in which the machine may be operated.

(A) is a base, or platform for the machine, and mortised into the base (A) is an upright post (B). Attached to the post (B) and extending therefrom sufficiently to be convenient for the feeding of papers is a 35 table (C) having formed in it an opening, for the follower (d) fully shown in Fig. 2. The follower (d), is formed with a recess (e) within which is arranged a spiral spring (f); inserted into the post, (B), and extending therefrom into the recess (e) is a plate (g), against which the upper end of the spring (f) is made to bear, while, the lower end of the spring is made to rest upon the follower, as fully shown in Fig. 2 by 40 means of which the said follower is made to return, after having been forced, up against, the face of the blocks.

(h) is a rod, pivoted to the treadle (i) at (i') and inserted into a mortise in the 50 follower (d).

(i) is a treadle, pivoted to the post (j) of the base (A), at (j') by means of which the follower (d) is made to operate through the medium of rod (h).

55 Firmly secured to the post (B) is a projection, (k), to which is attached the point-

ed bed (l). Said bed is made of a triangular form, having a base, barely sufficient to form a bed, or bearing for one of the wooden blocks, (r).

(n) is a friction lever, pivoted to the top of the post (B) at (B'), upon which is arranged the feed wheel (p)—the lever (n) is made to fit closely, in its bearings in the post (B) so that its friction therein may be 65 sufficient to sustain the wheel (p) in any required position.

(r) are wooden blocks made in the proper form and size so as, to be adapted, to the address required; in the face of these blocks (r) are formed indented letters; arranged in such manner as to print any address required. The blocks (r) are arranged in close columns upon a band or belt, (s), and are secured to said belt, by means of small tack nails, so that they may be readily arranged upon, or removed from the belt. By this arrangement of the blocks (r), upon the belt (s) we are enabled to place them in close compact columns, and thereby secure 80 a large number of names or addresses upon one belt.

Having described the construction of our invention; we will proceed to describe its 85 operation.

The block (r) being first prepared, with the proper indented letters in their faces, and then tacked onto the belt (s) as before described, the faces of the blocks will be inked by means of a suitable hand ink roller; the belt (s) with its blocks (r) will then be placed upon the feed wheel (p), passing around the pointed bed (l); the end (n') of the lever (n) will then be depressed, so as to tighten the belt (s) upon the feed wheel and bed; the operator, will now take hold of the feed wheel (p) with his left hand, and move it together with the band (s) until one of the blocks (r) is in proper position upon the bed (l) to deliver its impression, as clearly shown in Fig. 2. The operator will then place the newspaper upon the table (C) in proper position to receive the impression, and depress the treadle (i) with his foot, by means of which the follower (d) will be forced upward, through the medium of rod (h) in such manner as to bring the paper in contact with the block. A gentle pressure of the foot upon the treadle is then, sufficient 105 to perfect the operation of printing. The impression being made upon the paper, the 110

treadle is released, and the follower forced back by means of the spring (*t*). The feed wheel will be again turned, another block brought in position for printing, and 5 another paper fed to the machine and printed as before described, and this operation may continue until each block, has delivered its impression, when, the belt first used may be removed and replaced by 10 another similar one. The bed (*l*) being pointed at its lower end, serves to separate the blocks (*r*) at the printing point so that each block may deliver its impression as 15 perfectly as if alone upon the belt, as is clearly shown in Fig. 2.

We do not claim simply attaching letters or figures to flexible bands or endless chains operated by two or more pulleys one of 20 which acts as a bed piece for printing on. We are also aware that revolving or rotary machines and movements have been used for regulating and adjusting figures for paging

books, we do not design to use nor do we claim either of these devices. But

What we claim as our invention and de- 25 sire to secure by Letters Patent is—

1. The arrangement of wooden blocks (E) of suitable size for a single address with indented letters in their faces and attached by means of small tacks or equivalent 30 to a flexible band or belt, in close compact columns and operated substantially as de- scribed.

2. The use of the triangular stationary bed piece (*l*) over which the belt slides by 35 means of belt pulley (*p*) and regulated and adjusted by means of lever (*n*) substantially in the manner and for the purpose set forth.

R. W. DAVIS.
DANIEL DAVIS.
